UNITED STATES PATENT OFFICE.

JAKOB LÖLL, OF HOMBERG-ESSENBERG, GERMANY.

AUTOMATIC STEAM-PIPE-ISOLATING VALVE.

1,088,082.

Specification of Letters Patent. Patented Feb. 24, 1914.

Application filed September 7, 1912. Serial No. 719,205.

To all whom it may concern:

Be it known that I, JAKOB LÖLL, a subject of the Emperor of Germany, residing at Homberg-Essenberg, Germany, have invented 5 an Automatic Steam-Pipe-Isolating Valve, of which the following is a specification.

The present invention relates to a device for isolating the steam pipe automatically 10 from the boiler in case of a breakage.

The invention consists in the provision in the pipe of a lift valve adapted by spring pressure to be normally closed in opposition to the steam pressure. This valve is adapted 15 to be held in open position by a piston which is acted upon by the pressure normally prevailing at the discharge side of the valve. If the pressure should be lowered by a breakage of the pipe, the piston immediately 20 allows the valve to close. An additional piston, acted upon by the pressure prevailing at the inlet side of the valve, is provided for opening the valve initially to set the steam flowing through the pipe.

25 In the accompanying drawings the invention is illustrated, Figure 1 representing a longitudinal section of the device, Fig. 2, a section of the same showing the position of the elements when starting, and Fig. 3, 30 a sectional view showing the position after the starting.

A lift valve *b* is seated in the valve casting *a* and provided with a stem *c* guided through a cover plate *d* and a second plate *e*. A spring *f*, encircling said stem, is adapted to maintain said valve normally closed in opposition to the highest prevailing steam pressure. At opposite sides of the valve stem closed cylinders *g* and *h* are arranged in which move pistons *i* and *k* the rods of which are guided through the plate *e* and connected with each other by a cross-bar *m* which is passed through a slot in the valve stem. Said bar *m* is mounted in such 45 a manner in the three elements as to be able to assume the slanting positions shown in Figs. 2 and 3. Springs *l* encircle the two piston rods above the plate *e* which springs merely act as buffers and prevent the pistons 50 from descending below the position shown in Fig. 1. The steam pipes *n* and *o* communicate with the cylinders *g* and *h*, beneath the pistons, by means of branches *p* and *q* each of which is provided with a cock 55 (*p*¹, *q*¹) the branch *p* being also fitted with

a whistle *r* which is sounded while the cock *p*¹ is open.

The *modus operandi* is as follows:—In order to lift the valve *b*, which the steam pressure alone is incapable of doing, the 60 cock *p*¹ is opened, causing the steam to enter beneath the piston *i*. The surface of this piston being larger than that of the valve *b*, the piston is raised, the cross-bar *m* assumes the slanting position shown in Fig. 2, the 65 valve *b* is lifted, and the steam is set flowing through the pipe. Thereupon the cock *q*¹ is opened whereby the steam is permitted to enter the cylinder *h* beneath the piston *k*, raising the latter. The size of the piston *k* 70 is chosen with a view to insure the valve *b* being maintained in open position even if the steam pressure be unstable. As soon as the piston *k* is raised the cock *p*¹ should be closed whereupon the piston *i* descends to 75 the position shown in Fig. 3. In order to prevent the cock *p*¹ from being left open inadvertently, the whistle *r* sounds all the while the cock is open. During the undisturbed working the position of the device 80 shown in Fig. 3 is maintained. If a breakage in the pipe should occur, the consequently failing steam pressure beneath the piston *k* will immediately allow said piston to descend. By the action of the spring *f* 85 the valve *b* is forced into its seat and the flow of steam cut off. For closing the valve *b* whenever desired, it is only necessary to close the cock *q*¹, thus the device may be conveniently used as a stop valve. 90

It is obvious that various modifications may be effected within the scope of the invention.

I claim:—

1. An automatic steam pipe isolating 95 valve, comprising a lift valve guided by a stem, a spring acting on said valve so as to hold it normally closed in opposition to the steam pressure, two closed cylinders arranged at opposite sides of the valve stem, 100 pistons arranged respectively in said cylinders, guide rods connected to said pistons and held together with the valve stem in a common plane, a cross-bar connecting the rods and the stem so that the valve is opened 105 thereby when either of the pistons is raised in its cylinder, and means for setting one of said cylinders temporarily into communication with the steam pipe at the inlet side of the valve so as to raise its piston for opening 110 114

- said valve, the other cylinder being in communication with the pipe at the discharge side of the valve and its piston being adapted to be raised by the pressure and to hold the valve open as long as the pipe is intact and allow it to close if the pipe should break.
2. An automatic steam pipe isolating valve, comprising a lift valve guided by a stem, a spring acting on said valve so as to hold it normally closed in opposition to the steam pressure, a closed cylinder communicating with the steam pipe at the inlet side of the valve, a piston arranged in said cylinder and connected to the valve so as to open the latter when acted upon by the pressure, another cylinder communicating with the

pipe at the discharge side of the valve, a piston in the latter cylinder connected with the valve so as to retain the latter in open position under the influence of the pressure as long as the pipe is intact and allow it to close if the pipe breaks, means for interrupting the communications between the pipe and the cylinders, and a whistle arranged so as to be sounded as long as the first-mentioned cylinder is in communication with the pipe, substantially as and for the purpose set forth.

JAKOB LÖLL.
